UNITED STATES PATENT OFFICE

2,635,126

INTERNAL-COMBUSTION ENGINE

Martin C. Metzger, Buffalo, N. Y., assignor to
Worthington Corporation, a corporation of
Delaware

Application July 19, 1950, Serial No. 174,720

3 Claims. (Cl. 123—146.5)

1

This invention relates to internal combustion engines and more particularly to two and four cycle gas injection engines.

An object of the present invention is to provide means whereby explosions of unburned gas fuel in the exhaust piping of a gas fuel internal combustion engine will be prevented.

More specifically the present invention relates to a mechanism whereby the ignition switch and the fuel gas control valve are interlocked so that it will be impossible to manually turn on the fuel gas before the ignition system is turned on, and also it will be impossible to turn off the ignition switch until after the gas fuel to the engine is shut off.

In the drawings:

Figure 1 is a diagrammatic view partly in section and partly in perspective of an internal combustion engine equipped with the interlocking fuel and ignition circuit control mechanism.

Figure 2 is a side elevation of the control mechanism.

Figure 3 is a front elevation of the control mechanism having parts of the outer housing plate broken away.

Figure 4 is a section through the interlocking control mechanism taken on the line 4—4 of Figure 3.

Figure 5 is a detail elevation of the switch structure.

Figure 6 is a detail section taken on the line 6—6 of Figure 3.

Figure 7 is a detail elevation of the interlocking cam.

Figure 8 is a diagrammatic view partly in section and partly in perspective of a four-cycle gas fuel ignition fired internal combustion engine having the fuel and ignition control means applied thereto.

Referring more particularly to the drawings, an internal combustion engine gas fuel ignition fired two-cycle type is shown in fragment in Figure 1 of the drawings and includes the usual cylinder 1 in which the piston 2 reciprocates, and in which the gas fuel delivered to the cylinder 1 through the inlet pipe 3 is fired by a spark plug 4 which, as is usual in such constructions, is connected through a spark coil 5, timer 6, to a switch 7 which controls energizing of the spark plug and consequently the ignition of the fuel in the cylinder 1.

Fuel gas is delivered to the intake pipe 3 from any suitable supply source (not shown) through an inlet pipe 8 under control of a fuel gas control valve 9 operated by the governor 10 of the

2

engine. A fuel gas header 11 is shown connected between the fuel gas control valve 9 and intake pipe 3, but of course, this may be eliminated if desired.

5 A manually operated fuel delivery control valve 12 is mounted in the inlet pipe 8 outwardly of the fuel gas control valve 9 and it is operated manually upon the starting or stopping of the engine to control flow of fuel gas to the fuel gas control valve 9 and consequently to the engine.

The valve 12 is of any approved construction of rotary valve and it has a valve stem 13 connected thereto by means of which the valve is opened or closed. The valve stem 13 is connected to a stub shaft 14 (see Figure 4 of the drawings) which is rotatably supported by a suitable bearing structure 15. The bearing structure 15 is in turn carried by a support plate 16 attached as shown in Figure 2 of the drawings

10 at any suitable place to a part of the engine structure. The rotary stub shaft 14 has a handle 17 mounted thereon for rotating the stub shaft and consequently rotating the valve stem 13 for opening or closing the valve 12. A housing 18 is provided which encloses the shaft 14 and a quadrant 19. The quadrant 19 has a plurality of indentations 20 cut in its inner surface and a spring actuated latch 20 is carried by the handle 17 for engagement in any one of the notches 20 to hold the handle 17 in adjusted positions. The rod 22 is connected to the latch 20 and by pressing the button 23 on the end of the rod 22 the latch 20 is moved out of the notches 20 to permit movement of the handle 17. If it is so desired, an indicator 24 may be attached to the handle 17 which cooperates with an indicating dial 25 attached to the outer surface of the housing 18.

30 The ignition switch structure 7 includes a longitudinally slidable plunger 26 which extends through the outer front side of the housing 18 and has a button 27 formed on its outer end to facilitate manual reciprocating movement of the plunger. The inner end of the plunger 26 is connected in any suitable manner to the switch element or elements 28 so that when the plunger 26 is pushed inwardly into the position shown in Figures 2 and 4 of the drawings a circuit will be closed through the switch 7 to permit energizing of the spark plug 4.

35 The plunger 26 has a notch 30 cut therein intermediate its ends and this notch cooperates with a locking cam 33 which is keyed upon the shaft 14 so that it will move with movement of the handle 17 and the shaft 14. The locking

cam 33 has a concave portion 34 in its perimeter, the curvature of the edge of which corresponds to the curvature of the plunger 26, so as to permit the plunger to be moved longitudinally when the recess 34 registers with the plunger.

When the switch is in open position and the plunger 26 outwardly, the recess 34 engages over the plunger and prevents rotation of the shaft 14 and valve stem 13 so that when the ignition switch 7 is open and energizing of the spark plug 4 is cut off it will be impossible to open the valve 12 to permit fuel gas to flow to the engine. However, when the plunger 26 is moved inwardly to close a circuit through the switch 7 the interlocking cam 33 will then register with the notch 30 and permit movement of the handle 17 and rotation of the valve stem 13 for opening the valve 12. Thus it will be seen that fuel cannot be delivered to the engine, upon the starting of the engine until after the ignition switch has been closed and also that the ignition switch cannot be opened and the circuit broken through the spark plug 4 so long as the valve 12 is open because at such times the land 38 of interlocking cam 33 will be engaged in the notch 30 and will prevent longitudinal movement of the plunger. However, when the valve 12 is closed by movement of the handle 17 the recess 34 in the cam land will be positioned so as to permit the plunger 26 to be moved outwardly to break the circuit through the switch 7.

From the foregoing it will be seen that it will be impossible to turn on the manually operated fuel gas valve to allow fuel gas to flow to the engine until after the ignition switch is closed and that it will be impossible to open the ignition switch so long as the valve 12 is open and thus the delivery of live gas fuel to the cylinder and its expulsion into the exhaust line of the engine prior to ignition thereof will be prevented.

Figure 8 of the drawings embodies the same safety mechanisms operable in the same manner for preventing delivery of fuel gas to a four-cycle engine until after the ignition switch is closed and for preventing opening of the ignition switch so long as gas fuel is being delivered to the engine.

This form of the invention differs from that shown in Figure 1 of the drawings in that separate air and gas valves 40 and 41, respectively, under operation of the governor 42 of the engine, control the passage of air and gas into the chamber 43 where it is mixed prior to delivery to the intake passage 44. The fuel gas delivered to the passage 43 under operation of the valve 41 is controlled by the fuel gas inlet valve 45 which is identical to the valve 12. The valve 45 is opened and closed by a manually operated hand lever 46 through the medium of the valve stem 47 and a cam 48 is mounted upon the cam stem 47 for rotation therewith and it engages the switch closing manually operated plunger 49 which is the same as the plunger 26 for permitting or preventing movement of this plunger in the same manner as described in connection with Figure 1 for controlling the energizing of the spark plug 50 through the spark coil 51 and under control of the timer 52.

It will be understood that the invention is not to be limited to the specific construction or arrangement of parts shown, but that they may be widely modified within the invention defined by the claims.

What is claimed is:

1. The combination with an internal combustion engine including a cylinder, a spark plug for igniting fuel in the cylinder, a spark coil and a timer for controlling sparking of said spark plug and a fuel supply pipe for supplying fuel to the cylinder, of a switch for controlling flow of electric current to said spark coil whereby when said switch is closed said timer may make and break a circuit through said spark coil and said spark plug, a manually movable plunger for opening or closing said switch, a manually operable valve in said fuel supply pipe, a valve stem for operating said valve, a handle connected to said valve stem, a cam connected to said valve stem and rotatable with rotation of the valve stem, said plunger having a notch cut therein for receiving a portion of the land of said cam to permit opening of the valve when the control switch is closed, said cam having a concave peripheral portion therein engaging said plunger to prevent closing of the valve when said ignition switch is open.

2. The combination with an internal combustion engine including a cylinder, means for delivering fuel to said cylinder including a fuel supply pipe, and means for igniting fuel in said cylinder, of a valve in said fuel supply pipe, a manually rotatable element for operating said valve, a longitudinally movable plunger for controlling operation of said ignition means, a cam on said rotatable element and engaging said plunger to prevent rotation of the rotatable element when the plunger is in position to prevent operation of said ignition means.

3. The combination with an internal combustion engine including a cylinder, means for delivering fuel to said cylinder including a fuel supply pipe, and means for igniting fuel in said cylinder, of a valve in said fuel supply pipe, a manually rotatable element for operating said valve, a longitudinally movable plunger for controlling operation of said ignition means, a cam on said rotatable element and engaging said plunger to prevent rotation of the rotatable element when the plunger is in position to prevent operation of said ignition means, said plunger provided with a reduced area portion engageable with said cam to permit rotation of the rotatable element when the plunger is in position to permit operation of said ignition means and to prevent movement of the plunger when the valve is in open position.

MARTIN C. METZGER.
